UNITED STATES PATENT OFFICE.

TERRENCE CONNELL, OF HAVERFORD, PENNSYLVANIA.

ROCK-DRILLING BIT.

973,407.

Specification of Letters Patent. Patented Oct. 18, 1910.

Application filed July 21, 1909. Serial No. 508,811.

To all whom it may concern:

Be it known that I, TERRENCE CONNELL, a citizen of the United States, residing at Haverford, in the county of Montgomery and State of Pennsylvania, have invented new and useful Improvements in Rock-Drilling Bits, of which the following is a specification.

This invention relates to new and useful improvements in rock drilling bits and has more particular reference to a bit of that general type in which a number of radially disposed end cutting teeth are provided.

The object of the invention is to provide a bit of the above type in which the work is performed with a minimum expenditure of power and a minimum degree of resistance to the action of the cutting teeth. This object is accomplished by providing a bit of such construction that a partial cutting and a partial grinding effect is produced in a novel manner, the grinding or crushing action being an incident of the ordinary feeding and turning moments of the bit. Consequently, in the present construction a result is incidentally accomplished which in the ordinary constructions is objectively accomplished. It follows from the foregoing statement that the actual cutting area may be considerably reduced and therewith is had a reduction of the resistance encountered by driving the bit into the rock, the crushing or grinding action being, as stated, incidental, and offering very little and a far less degree of resistance to the bit than would be the case if the area to which the crushing action is confined, were cut, as in the ordinary construction.

In the accompanying drawings, I have illustrated by way of example, a preferred and advantageous embodiment of the invention.

In the said drawings: Figure 1 is a perspective view of a rock drilling bit constructed in accordance with the present invention. Fig. 2 is an end elevation thereof. Fig. 3 is a longitudinal sectional view thereof on the line 3—3 of Fig. 2 and Fig. 4 is a similar view thereof on the line 4—4 of Fig. 2.

Similar characters of reference designate corresponding parts throughout the several views.

The shank of the bit is indicated by the numeral 1 and is preferably constructed with a constricted axial duct, as 2, through

which a liquid or fluid may be forced or drawn, to carry away the dust produced as an incident of the operation of the bit. The said shank has at its working end, outwardly diverging ribs or facets, as 3, which may be of any desired number and arrangement and between which clearance grooves, as 4, for the passage of the aforesaid dust laden liquid or fluid, occur. The grooves 4 terminate at their outer ends in inversely curved facets, as 5, which extend forwardly in convergent relation for a comparatively short distance. The inner edges of the facets 5 are indicated by the numeral 6 and are also the bounding edges of a recess or opening 7 which is of inwardly tapering form and extends axially of the drill, the inner end of the recess or opening 7 meeting and being axially alined with the duct 2. The apices occurring at the junction of the inversely curved facets 5 are sharpened to constitute radial cutting teeth, as 8, which extend from the corners formed by the junction of the edges 6, to the median longitudinal lines of the ribs or facets 3.

The aforesaid recess or opening 7 is practically completely inclosed by the surrounding portions of the drill and consequently a maximum grinding and crushing area is afforded. Incidentally the edges 6 may be and preferably are sharpened to constitute cutting blades.

The arrangement herein shown is preferred, though not obligatory. In the present arrangement I employ four ribs or facets 3, a corresponding number of facets 5 and of teeth 8, a rectangular mouth bounded by the edges 6, and a recess or opening 7 of pyramidal form, as a consequence of which a series of lines drawn at different angles through the center of said opening will be of successively varying lengths, as is shown by a comparison of the widths of the opening in the two planes through which Figs. 3 and 4 are taken. The result of this is that the crushing pressure is gradually increased after its initial application and it follows that a more efficient crushing action is produced than would be the case if the crushing pressure were uniform.

In use, the teeth 8 will have a cutting action on an annular area, the width of which is determined by the extent of said teeth. At the center of this annular cutting area a pinnacle is left and this pinnacle is worn away as the bit is advanced by

virtue of a combined cutting and crushing action, the cutting action being produced by the edges 6 which take off the corners and sides of the pinnacle and the crushing action being produced by the tapered form of the opening or recess 7, the walls of which receive the said pinnacle in a wedge-like engagement of constantly increasing pressure which is exerted both 10 axially by virtue of the tapered form of the recess and also laterally by virtue of the square cross section or pyramidal form of the recess.

It follows from the foregoing description 15 that the advantages stated in the introductory paragraphs are efficiently attained, since the device operates with a minimum cutting area and a consequent minimum resistance and with a maximum 20 crushing area offering far less resistance than the equivalent cutting area found in the devices now known in the art. The structure incidentally preserves all the advantages of the known devices while adding thereto the novel advantages above set 25 forth.

Having fully described my invention, I claim:

1. A drill bit having its working end 30 formed with a series of radially disposed teeth arranged and proportioned to continuously produce a pinnacle on the material in which the cut is being made, and also with a centrally arranged flat-sided 35 recess having sharpened edge portions and having a degree of inward taper sufficient to produce the crushing and grinding of the pinnacle continuously with the original formation thereof throughout the cutting 40 operation.
2. A drill bit having its working face

formed with a series of facets, the apices of which are sharpened to constitute radial cutting teeth, and also with a centrally arranged inwardly tapering recess, the edges 45 of which are also the inner edges of the facets and are sharpened to constitute cutting teeth, the radial teeth producing a pinnacle on the material in which the cut is being made, continuously throughout the 50 cutting operation and the recess having a sufficient degree of inward taper to produce the grinding down and crushing of the pinnacle continuously with the original formation thereof.

3. A drill bit having the working end of its shank formed with outwardly divergent facets and with grooves alternating with the facets and terminating in outwardly converging facets, the apices of which are 60 sharpened to constitute radial cutting teeth which extend to the longitudinal centers of the several divergent facets, the bit also having at its working end a centrally arranged inwardly tapering recess, the bounding edges of which are also the inner edges of the convergent facets, the radial teeth producing a pinnacle on the material in which the cut is being made continuously throughout the cutting operation and the recess having a sufficient degree of inward 70 taper to produce the grinding down and crushing of the pinnacle continuously with the original formation thereof.

In testimony whereof I have hereunto set 75 my hand in presence of two subscribing witnesses.

TERRENCE CONNELL.
